UNITED STATES PATENT OFFICE.

JOHN CORYELL, OF DETROIT, MICHIGAN.

MULTIPLE-SCREW JACK.

1,896,258.

Specification of Letters Patent. Patented Nov. 3, 1932.

Application filed August 12, 1920. Serial No. 463,236.

To all whom it may concern:

Be it known that I, JOHN CORYELL, a citizen of the United States, residing at Detroit, in the county of Wayne and State of Michigan, have invented a certain new and useful Improvement in Multiple-Screw Jacks, of which the following is a specification.

This invention relates to multiple screw jacks of the type in which one screw rotates or telescopes inside the other. The object of the invention is to operate such a jack by a continuous rotary movement as distinguished from a ratchet movement and to do it in such a manner that the jack operates comparatively rapidly, thereby especially adapting it for light work such as on pleasure automobiles and light trucks. The invention consists in a novel combination of parts attaining the foregoing and other desirable objects which can be easily and comparatively cheaply made, which is satisfactory in the use and is not readily liable to get out of order. More in detail, the invention consists in many features and details of construction more fully set forth in the specification and claims.

Referring to the drawings in which like numerals denote like parts throughout the several views,

Figure 1 is a side sectional elevation of mechanism illustrating this invention in its preferred form.

Fig. 2 is a sectional plan view on the line 2-2 of Fig. 1.

The jack is supported upon a suitable base 10 having a foot 12 of ordinary construction adapted to rest from the floor. The side of this base 10 is preferably provided with a handle 14 by which the entire mechanism may be conveniently transported by the operator who takes hold of this handle. Telescopically mounted on this base 10 and guided for vertical movement only thereon by the handle 14 and the guide screw 16 entering suitable slots 17 and 19 respectively is a hollow case 18 preferably made in two parts, the upper one 18^a being a cover readily detachably securable in normal position by one or more securing devices, such as a series of circumferential set screws 20 only one of which is shown.

This base 10 is vertically bored and provided with screw threads 22 with which interfit the screw threads 24 on what will be

hereafter referred to as the lower or external screw 26. Rigidly secured to the upper end of this screw 26, in the particular case here illustrated integral therewith, is a bevel gear 28 inclosed within a chamber 30 formed in the case 18 below the cap 18^a. Intermeshing with this bevel gear 28 is a bevel pinion 32 mounted on a shaft 34 extending outside the case and adapted to be manually rotated by any suitable means, as for instance by a wrench (not shown) applied to the non-circular end 36 of this shaft 34.

The lower and outer screw 26 is hollow and its interior is provided with internal screw threads 38 of opposite pitch from threads 24, with which interfit screw threads 40 on what will be hereafter referred to as the inner or upper screw 42. This screw 42 carries at its upper end a load carrying block 44 rotatably mounted on the bearing member 46.

Extending along the length of the screw 42 is a keyway 48 slidably entered by a key 50 rigidly mounted in the hub 52 of a second bevel gear 54 journaled in the cap member 18^a of the case and meshing with and driven by bevel pinion 32, heretofore referred to. This will be referred to as a spline connection.

In the operation of the device, the operator places a wrench or the like on member 36 and rotates shaft 34 in a given direction thereby rotating pinion 32 in the same direction with the result that gears 28 and 54 rotate in opposite directions, thus rotating the screws in opposite directions with reference to each other, but moving both screws simultaneously in the same general direction with reference to the base 10. The result of this is that the ultimate lift by the load carrying block 44 is twice as great during the lifting operation as it would be if only one screw were used, and that the speed of lift is double, (assuming that the two sets of screw threads have the same pitch).

The base and case are each non-rotatable and will be referred to as non-rotatable members.

Having thus described my invention what I claim as new and desire to secure by Letters Patent, is:—

1. In mechanism of the class described, the combination of two separated non-rotatable members, one of which is a base, a pair of screws telescoping with each other

and with the non-rotatable members, screw threads between said screws, other screw threads between one screw and one non-rotatable member, a driving gear for the last mentioned screw, another gear for the other screw splined thereto and journaled in the other non-rotatable member, and means simultaneously rotating said gears in such directions that the screws travel in opposite directions longitudinally of each other and in the same direction with reference to the non-rotatable member in which one screw is threaded. 5

2. In mechanism of the class described, the combination of two separated non-rotatable members, one of which is a base, a pair of screws telescoping with each other and with the non-rotatable members, screw threads between said screws, other reversely pitched screw threads between one screw and one non-rotatable member, a driving gear for the last mentioned screw, another gear for the other screw splined thereto and journaled in the other non-rotatable member, and means simultaneously rotating said gears in such directions that the screws travel in opposite directions longitudinally of each other and in the same direction with reference to the non-rotatable member in which one screw is threaded. 10

3. In mechanism of the class described, the combination of two separated non-rotatable members, one of which is a base member, a pair of screws telescoping with each other and with the non-rotatable members, screw threads between said screws other reversely pitched screw threads between one screw and one non-rotatable member, a driving gear for the last mentioned screw, another gear for the other screw splined thereto, and journaled in the other non-rotatable member and means simultaneously rotating said gears in opposite directions so that the screws travel in opposite directions longitudinally of each other and in the same direction with reference to the non-rotatable member in which one screw is threaded. 15

4. In mechanism of the class described, the combination of two separated non-rotatable members, one of which is a base, means permitting reciprocation of one of said members with reference to the other, a pair of screws telescoping with each other and with the non-rotatable members, screw threads between said screws, other screw threads between one screw and one non-rotatable member, a driving gear for the last mentioned screw, another gear for the other screw splined thereto and journaled in the other non-rotatable member, and means simultaneously rotating said gears in such directions that the screws travel in opposite directions longitudinally of each other and in the same direction with reference to the non-rotatable member in which one screw is threaded. 20

5. In mechanism of the class described, the combination of two separated non-rotatable members, one of which is a base, means permitting reciprocation of one of said members with reference to the other, a pair of screws telescoping with each other and with the non-rotatable members, screw threads between said screws, other reversely pitched screw threads between one screw and one non-rotatable member, a driving gear for the last mentioned screw, another gear for the other screw splined thereto and journaled in the other non-rotatable member, and means simultaneously rotating said gears in such directions that the screws travel in opposite directions longitudinally of each other and in the same direction with reference to the non-rotatable member in which one screw is threaded, the gears and driving mechanism being all inclosed in and protected by one of the non-rotatable members. 25

6. In mechanism of the class described, the combination of two separated non-rotatable members, one of which is a base, means permitting reciprocation of one of said members with reference to the other, a pair of screws telescoping with each other and with the non-rotatable members, screw threads between said screws, other reversely pitched screw threads between one screw and one non-rotatable member, a driving gear for the last mentioned screw, another gear for the other screw splined thereto and journaled in the other non-rotatable member, and means simultaneously rotating said gears in opposite directions so that the screws travel in opposite directions longitudinally of each other and in the same direction with reference to the non-rotatable member in which one screw is threaded, the gears and driving mechanism being all inclosed in and protected by one of the non-rotatable members. 30

7. In mechanism of the class described, in combination with a base, one screw threaded into the base, a second screw inside the first screw, threaded therein, the screw threads between the base and the first screw being in one direction and the other set of screw threads being in the opposite direction, a pair of gears, one for each screw, means driving said gears in opposite directions, means rigidly securing one of said gears to one screw, and a spline connection between the other gear and the other screw, and a support for the last mentioned gear, for the purposes set forth. 35

8. In mechanism of the class described, in combination with a base, one screw threaded into the base, a second screw inside the first screw, threaded therein, the screw threads between the base and the first screw being in one direction and the other set of screw threads being in the opposite direction, a pair of gears, one for each screw, means driving said gears in opposite directions, means rigidly securing one of said gears to one screw, and a spline connection between the other gear and the other screw, and a support for the last mentioned gear, for the purposes set forth. 40

gear, for the purposes set forth. 125
8. In mechanism of the class described, in combination with a base, one screw threaded into the base, a second screw inside the first screw, threaded therein, the screw threads between the base and the first 130

5 screw being in one direction and the other set of screw threads being in the opposite direction, a pair of gears, one for each screw, means driving said gears in opposite directions, means rigidly securing one of said gears to one screw, and a spline connecting between the other gear and the other screw, a support for the last mentioned gear, a case inclosing the gear mechanism, and 10 means connecting said case to the base whereby the case may reciprocate with reference to the base, but may not rotate with reference to it.

9. In mechanism of the class described, 15 the combination of a base, a case telescopically mounted with reference to the base, but held against rotation with reference thereto, a pair of telescoping screws, screw threaded together, a reversely pitched screw threaded 20 connection between one of said screws and a base, a pair of bevel gears inside the case, one driving each screw, means simultaneously driving said gears in opposite directions, a spline connection between the screw 25 which is not in engagement with the base, and the gear which drives it, and a support for the last mentioned gear, for the purposes set forth.

10. In mechanism of the class described, 30 the combination of a base, a case telescopically mounted with reference to the base, but held against rotation with reference thereto, a pair of telescoping screws screw threaded together, a reversely pitched screw

35 threaded connection between one of said screws and a base, a pair of bevel gears inside the case, one driving each screw, means simultaneously driving said gears in opposite direction, a spline connection between the screw which is not in engagement with the base, and the gear which drives it, a support for the last mentioned gear, and a 40 load carrying block pivotally mounted on the end of the last mentioned screw, for the purposes set forth. 45

11. In mechanism of the class described, a base, a hollow case mounted for reciprocation on the base, means preventing rotation of the case on the base, a bevel gear in the case, a screw rigid with the bevel gear 50 passing through and screw threaded into the base, and oppositely placed bevel gear also in the case journaled in the case, means driving said gears operatable from outside the case, and a second screw passing through 55 both sets of gears and splined to the gear which is journaled in the case, passing through the first mentioned screw and threaded to it in threads of opposite pitch from the threads between the first screw 60 and base, for the purposes set forth.

In witness whereof, I have hereunto subscribed my name in the presence of two witnesses.

JOHN CORYELL.
